UNITED STATES PATENT OFFICE.

CLARENCE L. GREILICK, OF TRAVERSE CITY, MICHIGAN, ASSIGNOR TO TRAVERSE CITY CHAIR COMPANY, OF TRAVERSE CITY, MICHIGAN, A CORPORATION OF MICHIGAN.

MORRIS CHAIR.

1,151,099.

Specification of Letters Patent. Patented Aug. 24, 1915.

Application filed April 13, 1914. Serial No. 831,517.

To all whom it may concern:

Be it known that I, CLARENCE L. GREILICK, a citizen of the United States, residing at Traverse City, in the county of Grand Traverse and State of Michigan, have invented certain new and useful Improvements in Morris Chairs, of which the following is a specification.

My invention relates to improvements in Morris chairs, and has particular reference to a chair of this character embodying yieldable holding means to regulate or oppose the angular adjustment or movement of the back of the chair.

An important object of the invention is to provide a chair of the above mentioned character, so constructed that the back thereof may be conveniently angularly adjusted, and swung downwardly to substantially a horizontal position, when desired.

A further object of the invention is to provide adjustable means to regulate the extent of swinging movement of the seat of the chair in one direction, whereby the back thereof will assume a desired upright position.

A further object of the invention is to provide a chair of the above mentioned character, which is simple in construction, inexpensive to manufacture, strong, durable, and attractive in appearance.

Other objects and advantages of the invention will be apparent during the course of the following description.

In the accompanying drawings forming a part of this specification and in which like numerals are employed to designate like parts throughout the same, Figure 1 is an inside elevation of a chair embodying my invention, Fig. 2 is a central longitudinal sectional view through the same, Fig. 3 is a transverse sectional view taken on line 3-3 of Fig. 2, Fig. 4 is a similar view taken on line 4-4 of Fig. 2, Fig. 5 is a similar view with parts omitted, Fig. 6 is a transverse sectional view taken on line 6-6 of Fig. 2, and, Fig. 7 is a detail sectional view taken on line 7-7 of Fig. 1.

In the drawings, wherein for the purpose of illustration is shown a preferred embodiment of my invention, the numeral 10 designates a relatively stationary frame or body portion of the chair, comprising forward and rear legs 11 and 12, which are connected by transverse and longitudinal horizontal

rails 13, 14 and 15, as shown. The rails 13, 14 and 15 form in effect a relatively stationary open main frame. The forward and rear legs 11 and 12 extend upwardly beyond this main frame and carry horizontal arms 15', as is customary.

The numeral 16 designates an approximately horizontal seat or seat frame, embodying forward and rear transverse strips or elements 17, 18 and 19, which are rigidly connected by longitudinal strips or elements 20, as shown. This seat frame is preferably suitably covered with upholstering 21 of any well known or preferred type.

The numeral 22 designates a vertically swinging or angularly adjustable back disposed near the rear end of the seat 16, and arranged near and between the rear legs 12. This back is preferably suitably upholstered, in any well known or preferred manner.

Means are provided to pivotally connect the seat and back, the same comprising (see Fig. 7) a plate 23, rigidly secured to each edge of the back adjacent the lower end thereof, by means of screws or the like. 80 The plate 23 is provided upon its opposite longitudinal edges with outwardly extending flanges 24, and at its upper end with a stop flange 25. The flanges 24 are adapted to be inserted within longitudinal sockets 26, formed upon a co-acting hinge-leaf 27 (see Fig. 1). It is obvious that the plate 23 is thus securely held to the hinge-leaf 27, but may be removed therefrom by an upward longitudinal movement thereof with relation thereto. Each hinge-leaf 27 is provided near its lower end, as more clearly shown in Fig. 1, with a preferably angular extension 28, pivoted as shown at 29, with a coacting hinge-leaf 30, secured upon the outer edge 95 of the seat 16 adjacent the rear end thereof. Each hinge connection between the seat and back is supported by a vertically swinging link 31, pivoted to the hinge-leaf 27, as shown at 32. The lower end of the link 31 is pivotally connected with the longitudinal rail 15, as shown at 33. From the foregoing it is obvious that when the back 22 is

swung rearwardly from the vertical toward the horizontal, the rear end of the seat 16 will be elevated to be approximately horizontal and flush with the approximately horizontally arranged back, the forward end of the seat 16 being hinged to the transverse rail 13 to swing in a substantially vertical 110

plane, by means of hinges 34 or the like. Each link 31 being pivoted at its lower end, will swing upon its pivot, perceptibly, when the seat and back are moved, in angularly adjusting the back.

The numeral 35 designates a preferably slightly angularly arranged rail or track, inclined upwardly toward its forward end, the same being arranged to extend centrally and longitudinally within the main frame, and rigidly secured to the forward and rear transverse rails 13 and 14, as shown at 36. This rail or track is preferably inverted T-shaped in cross-section, as clearly illustrated in Fig. 6.

I will now proceed to describe the yieldable holding mechanism, preferably connected with the rail, and serving to control the angular adjustment or movement of the back and seat. The rear transverse strips 18 and 19 are spaced, as more clearly shown in Fig. 2, for receiving therebetween the yieldable holding mechanism, embodying, as more clearly shown in Figs. 4 and 5, outer horizontal reciprocating elements or blocks 37, having inner vertically inclined faces 38, forming therebetween a wedge-shaped opening, decreasing in width downwardly. Connected with the opposite ends of the elements 37, preferably by means of hooks 39, is a suitably stiff retractile coil spring 40, serving to move the elements 37 inwardly toward each other. Arranged between the outer reciprocating elements 37 is a vertical relatively stationary wedge-shaped co-acting element or block 41, decreasing in width downwardly. The vertically inclined faces of the wedge-shaped element 41 are preferably provided with strips 42 rigidly secured thereto by any suitable means and adapted to engage with the faces 38, said strips extending downwardly beyond the lower end of the element 41, providing fingers 43, to which are pivoted links 44, in turn pivoted to the rail 35, as shown. The outer elements 37 are slidably held upon plates 45, preferably connecting the transverse strips 18 and 19, the outer elements 37 being held against improper movement with relation to the seat by engagement with the top thereof.

The transverse rail 13 is provided with openings for receiving reciprocating bars 46, supported by strips 46', (see Fig. 6), having a foot-rest 47 hinged thereto, as shown at 48. The inner or rear ends of the bars 46 are connected by a transverse strip 49, (see Fig. 6) to which are secured guide elements 50, arranged upon opposite sides of the rail 35 and engaging the same. By virtue of the inclination of the rail 35 and the bars 46, when the foot-rest 47 is moved to its outer position, and swung to assume the horizontal position, it will be approximately horizontal and flush with the seat 16.

Adjustable means are provided to regu-

late the extent of downward movement of the rear end of the seat 16, the same comprising a bolt 51 preferably having screw-threaded engagement with the inner transverse strip 19, with its head engaging a portion of the rail 35. The function of this means is to control the angular position that the back 22 will assume, when swung upwardly to the end of its movement in that direction.

The inner wedge-shaped element 41 is held against vertical movement, and the connections between the seat and back cause the rear end of the seat to be elevated upon the movement of the back in one direction. When the back 22 is swung toward the horizontal the outer elements 37 will be moved outwardly away from each other in opposition to the retractile coil spring 40, thus properly retarding the movement of the back. It is thus seen that yieldable holding means are provided to control or oppose the swinging movement of the back in one direction, such means operating through the medium of the seat. When the back is swung toward the vertical, the opposite of this operation occurs. By the construction of my chair the back may be swung to a substantially horizontal position, the seat being elevated to be flush therewith. The foot-rest may be moved to the outer position to be substantially flush with the seat and back. The chair will then be about as comfortable as a couch or lounge. By adjusting the bolt 51, the extent of downward movement of the seat 16 may be regulated, for controlling the precise angle that the back 22 will assume when swung to the end of its upward movement.

It is to be understood that the form of my invention herewith shown and described is to be taken as a preferred example of the same, and that various changes in the shape, size, and arrangement of parts may be resorted to without departing from the spirit of the invention or the scope of the subjoined claims.

Having described the invention, I claim:

1. In a chair of the character described, a relatively stationary body portion, a vertically movable seat, a horizontally movable element carried by the seat, a relatively stationary coacting element arranged for slideable engagement with the horizontally movable element, a spring to oppose the movement of the horizontally movable element in one direction, an angularly adjustable back, and connecting means between the back and seat whereby said back will move the seat upwardly upon being swung toward the horizontal.

2. In a chair of the character described, a relatively stationary body portion, a vertically movable seat arranged therein, a horizontally reciprocating element provided

with an inclined engaging face and carried by the seat, an upstanding co-acting element provided with an inclined engaging face to coöperate with the first named inclined engaging face, means to hold the upstanding element against undue vertical movement, a vertically swinging back pivotally connected with the relatively stationary body portion near one end of the seat, and connecting means between the back and the seat whereby the seat will be raised upon the back being swung toward the horizontal.

3. In a chair of the character described, a relatively stationary body portion, spaced horizontal reciprocating elements provided with inner vertically inclined engaging faces and carried by the seat, a wedge-shaped element decreasing in width downwardly and arranged between the inclined engaging faces of the first named elements, means to oppose the movement of the first named elements away from each other, means to prevent the upward movement of the wedge-shaped element, a vertically swinging back, and connecting means between the back and the seat whereby the back may elevate the seat upon being swung toward the horizontal.

4. In a chair of the character described, a relatively stationary body portion, a vertically movable body supporting member arranged therein, guide means carried by the

body supporting member, a plurality of elements movably mounted within the guide means and having wedging engaging faces, an element arranged between the first named elements and having wedging engaging faces, a retractile coil spring connecting the said plurality of elements to oppose their spreading movement, and means to connect said element with the relatively stationary body portion.

5. In a chair of the character described, a relatively stationary body portion, a vertically movable body supporting member disposed near the same, a substantially horizontally movable element carried by the body supporting member and provided with a downwardly inclined face, a relatively stationary co-acting element provided with an upwardly inclined face engaging with the downwardly inclined face of the first named element whereby a wedging action occurs upon the upward movement of the body supporting member, and spring means to move the substantially horizontally movable element in one direction.

In testimony whereof I affix my signature in presence of two witnesses.

CLARENCE L. GREILICK.
